UNITED STATES PATENT OFFICE.

OAKLEY T. LEE, OF BROOKLYN, NEW YORK.

DISH OR PLATE LIFTER.

SPECIFICATION forming part of Letters Patent No. 271,340, dated January 30, 1883.

Application filed December 11, 1882. (No model.)

To all whom it may concern:

Be it known that I, OAKLEY T. LEE, of Brooklyn, in the county of Kings and State of New York, have invented an Improvement in 5 Dish or Plate Lifters, of which the following is a specification.

A lifter for handling hot dishes or plates has been made of two wires with hooks on the end and a double wire finger sliding on the 10 said two wires and a handle at the end of such wires. In this case the wire fingers are liable to slip on the wires, and the handle is so remote from the fingers that the lifter cannot be operated by one hand. Besides this the wires 15 are liable to be brought into contact with the surface of the pie or other article.

My invention is made for obviating the aforesaid difficulties; and it consists in a sliding finger upon the hooked rods, constructed so as 20 to clamp upon the rods by the pressure from the article lifted. I also dispense with any separate handle, and form the lifter-rods so that they can be grasped at the finger, and the thumb be used to either relieve the finger or 25 move it up against the plate, dish, pan, or other utensil that is either hot or dirty.

In the drawings, Figure 1 is a side view of the lifter, partially in section. Fig. 2 is a plan of the same, and Fig. 3 is an inverted plan of 30 the finger.

The wire made use of is sufficiently large and strong for the intended use. It is bent double at *a*, and the two rods *b b* are slightly diverging, and near the ends they diverge considerably, as at *c*, and are bent downwardly, 35 as seen in Fig. 1, and terminate as hooks *d*.

The sustaining-finger *e* is made as a casting, and the upper part has the loops or eyes 2 and 3, that slide upon the rods *b b*. There is a 40 plate, 4, that is at the upper part of the finger and extends across below the rods *b*.

Upon reference to Fig. 1 it will be seen that the plate *h*, or other article, when grasped between the hooks and finger, is at some distance 45 below the rods *b b*, the edge of such dish or plate occupying the bends of the hooks *d*. Hence the rods *b b* will not come into contact with the top of a pie, should the lifter be used with such an article; neither will the dish or

plate be liable to slip in consequence of an insufficient hold. The finger *e*, when pushed along by the thumb or finger, passes under the edge of the plate or other article, as shown, and the person grasping the rods in lifting the article causes the rods to bind against the 50 sides of the eyes or loops 2 2 of the finger *e*. Furthermore, the downward pressure upon the front of the finger *e* causes the back corner, 6, of the plate portion 4 to bind against the under sides of the rods *b*, and the front edge of 55 the eyes or loops 3 to bind upon the top surfaces of the said rods, thereby producing a holding action that prevents the finger sliding back upon the rods. Besides this the thumb of the person using the lifter will usually rest 60 against the upper back portion of the sliding finger to keep it up to place. When the article that has been lifted is placed on a table or other support the pressure upon the curved end of the finger is relieved, so that it no 65 longer binds upon the rods, and it can be drawn back to detach the lifter from the plate or other article.

I claim as my invention—

1. The combination, with the rods *b* and 70 hooks *d*, of the finger *e*, having the eyes or loops sliding upon the rods *b*, and forming a clamp that binds upon the rods *b* by the action of the weight of the article lifted, substantially as set forth.

2. In a lifter for plates and other articles, the wire bent double to form the parallel or nearly parallel rods *b b*, the hooks at the ends of the rods, and downwardly-bent portion *c*, in combination with the sliding finger, substantially as set forth.

3. In a plate-lifter, the combination, with the rods *b*, with hooks at their ends, of the cast-metal finger having a curved end, and eyes or loops sliding on the rods and acting to clamp 80 the same, substantially as set forth.

Signed by me this 7th day of December, A. D. 1882.

OAKLEY T. LEE.
